UNITED STATES PATENT OFFICE.

YASUTARO KAWAKAMI, OF DAWSON, YUKON TERRITORY, CANADA

IRONING-MACHINE.

No. 921,120.

Specification of Letters Patent. Patented May 11, 1909.

Application filed January 16, 1908. Serial No. 411,113.

To all whom it may concern:

Be it known that I, YASUTARO KAWAKAMI, a subject of the King of Great Britain, residing at Dawson, in the Yukon Territory, 5 Dominion of Canada, have invented certain new and useful Improvements in Ironing-Machines; and I do hereby declare the following to be a full, clear, and exact description of the invention, such as will enable others 10 skilled in the art to which it appertains to make and use the same.

This invention relates to new and useful improvements in ironing machines and it has more particular reference to a manually 15 operated ironing machine embodying in its general construction an ironing roller and spring held means for holding said roller upon the ironing table.

In connection with an ironing machine of 20 the above type, the invention aims as a primary object to provide in connection with the ironing roller, novel spring means for holding the same to the table.

The invention aims as a further object to 25 provide a novel handle for the roller, such handle including resilient side arms designed to engage the roller, and novel clamping means for holding said side arms in such engagement.

30 The details of construction will appear in the course of the following description, in which reference is had to the accompanying drawings, forming a part of this specification, like characters of reference designating 35 similar parts, throughout the several views, wherein:

Figure 1 is a top plan view of an ironing machine constructed in accordance with the present invention. Fig. 2 is a side elevation 40 thereof. Fig. 3 is a section on the line 3—3 of Fig. 1, looking in the direction of the arrow and showing more particularly the clamping means above referred to. Fig. 4 is a section on the line 4—4 of Fig. 1. Fig. 5 is a detailed perspective view of a clamping lever 45 included in the invention.

In the accompanying drawings, the numeral 5 designates an ironing table and the numeral 6 designates generally the machine 50 forming the subject matter of the present invention. Such machine comprehends a hollow ironing roller 7, having openings 8 in the sides thereof, through which heating flames may be introduced. The roller 7 is 55 actuated by means of a handle 9, comprising a U-shaped metallic part 10, having resilient

arms 11 and having secured to its cross part, a wooden hand grip 12. The arms 11, at their extremities, are formed with collars 13, having tubular extensions 14, which extensions are designed for engagement in openings 15 formed centrally in the sides of the roller 7. In such engagement of the tubular extensions 14 in the roller 7, a rod or shaft 16 passes through the collars and centrally 60 through the roller, and projects on each side beyond the sides of the table 5. The ends of the rod 16 are formed as eyes 17, through which are engaged the hook-shaped upper ends 18 of retractile coil springs 19, said springs 70 having their lower ends bent into hook shape as at 20 and engaged with pins 21 carried by arms 22. The arms 22 are pivoted at their front ends as at 23 to the frame of the table 5 and at their other ends are connected by a cross part 24 which carries a projecting treadle 25. It will be apparent that by depressing the arms 22, by means of the treadle 25, the tension of the springs 19 will be increased, so that the roller 7 is caused to bear 80 with greater force upon the articles to be ironed.

The means for holding the arms 11 with their collar extensions engaged in the openings 15 of the roller 7, comprises two yokes 85 26 and 27 of substantial U-shape, the yoke 27 being narrower than the yoke 26, and having its inner ends disposed between the inner end portions of said yoke 26. The yokes 26 and 27 are engaged in selected notches 28, 90 formed in series in plates 29, which plates are secured to the respective arms 11. The inner ends of the yokes 26 and 27 are bent into the form of hooks 30 and 31, the hook shaped ends of the respective yokes confronting one another and being engaged with respective pins 32 and 33, provided at one end of a clamping lever 34. The lever 34 is of curved form and at its other end carries a handle 35, which in the position of parts 100 shown, bears against the yoke 26.

In use, the machine is reciprocated over the table 5, the operator grasping the handle grip 12. When the ends of the springs 19 are disengaged from the rod 16 the rod can be withdrawn from the roller. After the said rod has been withdrawn from the roller the lever 34 is swung into a position so as to have its pins 32 and 33 release the hooks 30 and 31 of the yokes 26 and 27 respectively which will 110 permit the spreading apart of the spring arms 11 and thereby disengaging the ex-

tensions 14, from the openings 15 in the roller, which will result in the freeing of the roller.

The invention is simple in its structural details, inexpensive to manufacture and practical and efficient in use.

What is claimed is:

1. The combination with a work support, of an ironing roller having central openings in opposite sides thereof, a shaft mounted in said openings and extending beyond the work support and containing perforations near opposite extremities, a handle comprising resilient arms terminating in collars surrounding the shaft, said collars provided with extensions to engage in the openings in the roller, a foot treadle, and springs mounted on said treadle and having connection with the perforated ends of said shaft.
2. In an ironing machine, an ironing roller, a rod passed centrally through the latter, a handle having arms provided with collars surrounding the rod, tubular extensions formed on the collars and detachably engaging the roller at opposite sides thereof, a foot treadle, and yieldable means having connection between the foot treadle and the ends of said rod.
3. In an ironing machine, an ironing roller, a rod passed centrally through the latter, a handle having arms provided with collars surrounding the rod, tubular extensions formed on the collars and detachably engaging the roller at opposite sides thereof, a foot treadle, yieldable means having connection between the foot treadle and the ends of said rod, and means operable upon

the arms to hold the tubular extensions in engagement with the roller.

4. In an ironing machine, an ironing roller, a rod extending centrally through the roller, a handle having spreading arms, slideable on the rod to detachably engage with the roller, a foot treadle, spring connections between the treadle and said roller, and U-shaped yokes embracing said arms and extended inwardly, the inner end portion of one of said yokes being disposed between the side pieces of the other yoke, said yokes being formed at their inner ends with confronting hooks and a curved clamping member provided with two pins for engagement with said respective hooks in their confronting relation.

5. In an ironing machine, an ironing roller, a handle comprising resilient arms formed for detachable engagement with the sides of said roller and adapted to spring outwardly therefrom, and means for holding said arms in such engagement, said means comprising U-shaped yokes embracing said arms and extended inwardly, the inner end portion of one of said yokes being disposed between the side pieces of the other yoke, said yokes being formed at their inner ends with confronting hooks, and a curved clamping lever provided with two pins for engagement with said respective hooks in their confronting relation.

In testimony whereof, I affix my signature, in presence of two witnesses.

YASUTARO KAWAKAMI.
